UNITED STATES PATENT OFFICE.

ANTONIO BONGIOVANNI, OF BARNESBORO, PENNSYLVANIA.

RAZOR-CLEANING ATTACHMENT FOR BARBERS' CHAIRS.

1,095,448.

Specification of Letters Patent.

Patented May 5, 1914.

Application filed January 27, 1913. Serial No. 744,570.

To all whom it may concern:

Be it known that I, ANTONIO BONGIOVANNI, a citizen of the United States, residing at Barnesboro, in the county of Cambria and State of Pennsylvania, have invented a new and useful Razor-Cleaning Attachment for Barbers' Chairs, of which the following is a specification.

The invention relates to improvements in 10 razor cleaning attachments for barbers' chairs.

The object of the present invention is to improve the construction of razor cleaning attachments for barbers' chairs, more especially that shown and described in Patent 15 No. 1,089,311, dated March 3, 1914, and to provide a simple, inexpensive and efficient razor cleaning attachment, adapted to present a neat and attractive appearance, and 20 equipped with an adjustable mirror and with means for holding an antiseptic for sterilizing razors, and provided also with a receptacle adapted to receive the lather wiped from a razor.

25 A further object of the invention is to provide a lather receptacle adapted to be easily and quickly applied to and removed from the attachment, so that the same will be provided with a clean sanitary cup for each 30 customer and having a yieldable wiping surface, which will not injure the edge of a razor or affect the keenness thereof.

With these and other objects in view, the invention consists in the construction and 35 novel combination of parts hereinafter fully described, illustrated in the accompanying drawing, and pointed out in the claims here-to appended; it being understood that various changes in the form, proportion, size and 40 minor details of construction, within the scope of the claims, may be resorted to without departing from the spirit or sacrificing any of the advantages of the invention.

In the drawing:—Figure 1 is a perspective view of a razor cleaning attachment, constructed in accordance with this invention. Fig. 2 is a vertical sectional view of the upper portion of the attachment, the mirror arm being swung forward to a position at right angles to the receptacle supporting arm and the section being taken longitudinally of the receptacle supporting arm and passing transversely through the mirror supporting arm. Fig. 3 is a detail view, illustrating the manner of mounting the adjustable mirror. Fig. 4 is a detail per-

spective view of the upper end of the standard.

Like numerals of reference designate corresponding parts in all the figures of the 60 drawing.

In the accompanying drawing, in which is illustrated the preferred embodiment of the invention, 1 designates a standard constructed of any suitable material preferably metal, and designed to be finished in any suitable manner, and having its lower portion 2 curved and arranged at a slight inclination to offset a lower integral terminal attaching portion 3 from the vertical plane of the body 65 portion of the standard 1. The lower terminal attaching portion 3 is preferably in the form of a plate, tapered, as shown, and provided with perforations 4 for the reception of screws, or other suitable fastening 70 devices for securing the standard to any 75 convenient portion of a barber's chair.

The standard 1, which is preferably semi-tubular to secure strength and lightness and to present a rounded outer surface, is provided at its upper end with an integral circular head 5, provided with a central opening 6 in which is fixed a vertical pivot 7, having a threaded upper portion 8 for the reception of a thumb nut 9 for securing a 80 horizontal receptacle supporting arm 10, and a mirror supporting arm 11 on the pivot. The horizontal arm 10, which is constructed of suitable metal, is provided at its inner 85 end with a perforation 12 to receive the pivot, and it is arranged upon the head 5, which is provided at its upper face with an annular series of radially arranged ribs 13, presenting a rough surface to the lower face of the inner end of the receptacle supporting arm and adapted to retain the same in its pivotal adjustment, the arm 10 being adapted to be swung around the pivot 12 to any desired position to suit the convenience 90 of the barber and to arrange it out of the way while the barber is cutting hair, shampooing the head, or the like. The weight of 95 the horizontal arm is sufficient to maintain a proper frictional engagement between it and the rib or serrated upper face of the head 5. The parts may be positively held in any adjustment by tightening the thumb nut 9.

The horizontal arm 10 is provided at its outer end with a circular opening 14, preferably formed by a ring-shaped terminal portion 15, which supports a shallow lather

receiving cup 16. The terminal ring-shaped portion 15 has downwardly and inwardly tapered sides, and the shallow cup or receptacle 16 is correspondingly tapered and extends 5 slightly below the lower edge of the ring-shaped portion. The cup or receptacle 16, which is preferably constructed of rubber, is provided at its upper edge with an outwardly extending annular flange 17, resting upon 10 the upper edge of the ring-shaped portion and supported by the same and rounded at its upper face 18 to present a yieldable wiping edge to a razor. The terminal ring-shaped portion besides supporting the cup stiffens 15 the yieldable projecting annular flange 17 sufficiently to enable razors to be wiped across the rounded upper face of the flange without materially indenting the flange. By 20 this construction, the cup may be constructed of soft rubber, or other suitable material, and there will be no liability of accidentally cutting the same in wiping a razor thereon. The lather falls into the cup or receptacle when the blade of a razor is wiped across 25 the flange 17, and the shallow receptacle is adapted to be readily placed in and removed from the supporting arm, so as to be readily cleaned and sterilized after each shaving operation, thereby insuring a 30 clean sanitary lather cup for each customer. The receptacle supporting arm is also provided at a point intermediate of its ends with a rectangular opening 19 formed in an enlarged portion 20 of the arm 10 ad- 35 jacent to the inner end thereof, and receiving an antiseptic receptacle 21. The receptacle 21, which extends above and below the arm 10, is rectangular in cross section and is designed to be of a sufficient length to re- 40 ceive the cutting portion of the blade of a razor, and it is adapted to contain liquid or other disinfectant for sterilizing razors. For this purpose, it is preferably equipped with a removable glass vessel 22, conforming to 45 the configuration of the interior of the receptacle 21 and adapted to be readily taken from and replaced therein for cleaning or other purposes. The exterior of the receptacle 21 is preferably provided at an inter- 50 mediate point between its top and bottom with a slightly tapered portion 23, presenting downwardly and inwardly inclined faces to the walls of the opening 19, which walls are correspondingly inclined to form a seat 55 for the said receptacle 22. Any other suitable means, however, may be employed for supporting the antiseptic receptacle within the opening of the arm 10. The antiseptic receptacle is preferably equipped with a 60 horizontal cover 24, provided at one of its corners with a projecting ear 25, pierced by a vertical pivot screw 26, which is mounted in an enlargement 27 of the receptacle 22.

The mirror supporting arm 11, which is 65 composed of upper and lower substantially

vertical portions and an intermediate horizontal connecting portion, is provided at its lower end with a projecting ear 28 having an opening for the reception of the vertical pivot 12, and reduced at its lower face at 29 70 to fit in a recess 30 in the upper face of the pivoted end of the horizontal arm 10, as clearly shown in Fig. 2 of the drawing. The upper vertical portion of the arm 11 extends through an opening 31 in a projecting lug or portion 32 extending centrally from the back of a mirror 33 and having a set screw 34 for engaging the arm 11 to secure the mirror in any adjustment. The lower vertical portion is of a length to extend above the top of the antiseptic receptacle, so that the mirror supporting arm will swing clear of the same in the adjustment of the mirror. The mirror, which may be of any preferred construction, is adjustable vertically on the standard, and is adapted to swing around the same and it may be arranged in various positions to enable it to be adjusted, after a hair cutting operation, to permit the customer to view the back of his head and thereby obviate the necessity of the barber holding a mirror, which is the usual custom in barber shops. The pivoted screw and the thumb nut form a detachable connection between the mirror supporting arm and the 80 standard, and the mirror may be removed from the attachment when desired. 90

What is claimed is:—

1. An attachment of the class described including a standard provided at its upper 100 end with a head, a pivot carried by the said head, a horizontal receptacle supporting arm mounted on the pivot and having an interlocking engagement with the head for holding the said arm in its adjustment, and a superimposed supporting arm also mounted on the said pivot and being free to swing around the same and arranged upon and maintaining the receptacle supporting arm in its interlocked relation with the head of 105 the standard. 110

2. An attachment of the class described including a standard, an arm mounted on the standard and provided with inner and outer openings, a lather receptacle detachably fitted in the outer opening, and an antiseptic receptacle removably mounted in the inner opening and extending through the said arm and projecting above and below the same. 115

3. An attachment of the class described including a supporting arm provided with an opening, and a receptacle carried by the arm and removably arranged in the said opening and provided at its upper edge with 120 an outwardly projecting flange constructed of yieldable material and resting upon and supported by the arm and presenting an upper wiping face. 125

4. An attachment of the class described 130

including a supporting arm provided with an opening having downwardly and inwardly inclined walls, and a downwardly tapered shallow receptacle removably fitted 5 in the opening and fitting the walls thereof and provided at its upper edge with an outwardly projecting flange constructed of yielding material and resting directly upon the said arm at the opening thereof and presenting an upper yieldable wiping surface. 10 5. An attachment of the class described including a standard provided at its upper end with a head, an article supporting arm extending from the head, said head and 15 arm having coacting interlocking means, a superimposed article supporting arm extend-

ing from the upper end of the standard, and a single pivot mounted on the standard and common to both of the said arms and connecting the same to the standard, said superimposed arm being freely movable around the said pivot and resting upon the other arm and maintaining the latter in its interlocked relation with the head of the standard. 20

25 In testimony, that I claim the foregoing as my own, I have hereto affixed my signature in the presence of two witnesses.

ANTONIO BONGIOVANNI.
